Attorney, Agent, or Firm—Harpman & Harpman[57] **CLAIM**The ornamental design for a box for a chocolate figure, as
shown and described.**DESCRIPTION**

FIG. 1 is a front, top and side perspective view of a box for a chocolate figure showing our new design;
FIG. 2 is a front elevational view thereof;
FIG. 3 is a rear elevational view thereof;
FIG. 4 is a right side elevational view thereof; the left side
elevational being a mirror image thereof; and,
FIG. 5 is a bottom plan view thereof.

The bottom is unornamented. The broken line showing of a
chocolate figure is for illustrative purpose only and forms no
part of the claim.
